FRANK S. CHAPMAN, OF TOLEDO, OHIO, ASSIGNOR TO THE NATIONAL ELECTRIC SPECIALTY COMPANY, OF TOLEDO, OHIO, A CORPORATION OF OHIO.

LIGHTNING-ARRESTER.

1,173,096.

Specification of Letters Patent.

Patented Feb. 22, 1916.

Application filed May 20, 1910. Serial No. 562,416.

To all whom it may concern:

Be it known that I, FRANK S. CHAPMAN, a citizen of the United States, residing at Toledo, in the county of Lucas and State of Ohio, have invented certain new and useful Improvements in Lightning-Arresters, of which the following is a specification.

My invention relates to a lightning arrester and has for its object to provide a device of this sort having certain new and improved constructions and arrangements to be hereinafter described and claimed.

One of the objects of the invention is to provide a lightning arrester constructed with a gap, or with gaps, across which a static current of short duration, like a lightning discharge, may pass to ground without overheating or otherwise injuring the electrodes, and provided with means whereby the gap is closed in the event that a continuous current of relatively high potential gets on the line, as for example, when the line becomes crossed with a high potential power line or the like, in which case, if such a current were permitted for any considerable length of time to arc across the gap or gaps between the electrodes, the latter might be heated enough to destroy the usefulness of the lightning arrester.

A further object of the invention is to provide in a lightning arrester, comprising electrodes contained within a vacuum chamber, a firm and durable mounting for the electrodes which will always keep the electrodes in the same relative positions.

A further object of the invention is to provide a simple and convenient device whereby the lightning arrester may be so mounted that it can be removed, for repair or when it has to be replaced by a new one, without disconnecting the line and ground wires.

A further object of my invention is to provide a lightning arrester of the vacuum type in which a shield shall be interposed between the arcing zone and the adjacent surface of the exhausted container, especially the surface where the wires come through the container, whereby the container as well as the wires are protected against the heat generated by the arc when the device discharges under a high potential.

A further object of my invention is to provide such a device in which the inter-

posed shield shall be separated from the protected surface of the container.

Another object of my invention is to connect the carbon electrodes with the ground and line wires by an intermediate member in such a manner as to lessen the tendency to melt the wires.

These and such other objects as may hereafter appear are attained by my invention as hereinafter set forth and described.

The invention is illustrated in a preferred embodiment in the accompanying drawings, wherein—

Figure 1 is a longitudinal sectional view, with parts shown in elevation, of the lightning arrester. Fig. 2 a sectional plan taken on line 2—2 of Fig. 1. Fig. 3 a sectional plan taken on line 3—3 of Fig. 1. Fig. 4 a side elevation of one of the electrodes, the upper part being shown in section. Fig. 5 a diagram illustrating the wiring for a metallic circuit. Fig. 6 a similar view illustrating the wiring for a grounded line. Fig. 7 a perspective view illustrating a preferred form of device for mounting the lightning arrester. Fig. 8 a perspective view of one of the porcelain blocks shown in the preceding figure, looking at the bottom of the same, and Fig. 9 a section taken on line 9—9 of Fig. 7, looking in the direction of the arrows.

Like characters of reference indicate like parts in the several figures of the drawings.

Referring to the drawings, 15 designates a porcelain base on which are mounted a pair of electrodes 16 consisting preferably of carbon plates, between which is a third carbon plate 17. The carbon plates 16 and 17 are secured to the base 15 by means of the screws 18 which screw into extensions 19 at the bottom of the electrodes; the screws 18 serving also as binding posts for the leading-in wires, as will be hereinafter described. Preferably, the electrodes 16 and 17 are additionally secured to the base by means of a body of asbestos cement 20 which embeds the lower ends of the electrodes, as shown. By this arrangement it will be observed that during a discharge of the device the carbon electrodes will first become heated and by the indirect method of connecting the carbons with the leading in wires the tendency to overheat the wires will be lessened. Furthermore, in arresters of the vacuum

type the heat generated by the arc during the discharge of the device is so intense that it has a tendency to melt the wall of the glass container when the same is exposed to the direct heat of the arc and also has a tendency to crack the glass, thereby admitting air and destroying the vacuum, whereupon, because of the wide gap between the electrodes provided in a vacuum arrester and the higher resistance of atmospheric air, the device becomes inoperative. So, also, the intense heat of the arc tends to burn off the leading in wires unless protected. It will be seen, therefore, that I have interposed a shield between the arcing zone and that portion of the container through which the leading in wires pass, consisting, first, of a porcelain base which is a more highly refractory material than glass, second, preferably of a layer of asbestos cement interposed between the arcing zone and the porcelain base, and thirdly by separating the porcelain base from the adjacent glass wall. Thus in the preferred embodiment of my invention as shown in Fig. 1, I provide a protective shield for the leading in wires and a durable protection for the glass wall, especially at the point where it is most likely to be cracked, to wit, where the leading in wires pass through the glass. At the same time I provide a firm mounting for the electrodes, whereby they are effectively secured in position at the proper distance from each other, a matter of great importance in such service as railroad work, where devices are subjected to the constant vibration of passing trains.

The electrodes 16 are provided with metal cups 21 which contain the bodies of solder 40 22, the latter being employed to secure in place the, preferably, iron balls 23. The balls 23 have a diameter greater than the distance between the rims of cups 21 and the adjacent surfaces of the center electrode 45 17. It will be understood, of course, that these separable balls or similar contact points are not essential to the broad features of my present invention in certain of its aspects above noted, but constitute a modification 50 which it is desirable to use in certain situations or for particular services.

The electrodes and the base on which they are mounted are contained within a glass bulb 24, or other suitable inclosing means, 55 from which the air has been partially exhausted; the degree of vacuum depending upon the size of the spark gaps, upon the sort of line on which the device is to be used and other obvious considerations relating to 60 the design of the device.

The device as described is intended to be used on a metallic circuit, the general relation of the parts being shown in the diagram of Fig. 5. A, in this figure, represents the 65 instrument to be protected, B the line wire,

25—25 wires leading from the line wire B on each side of the instrument A to the electrodes 16; and 26 a wire leading from electrode 17 to the ground.

For reasons which are well understood 70 the portions of the leading-in wires of the device which pass through the glass stem 27 are made of platinum, these sections of wire being indicated at 28. The wires 25—25 and 26 are ordinarily copper. Preferably, in order to give a firm and rigid support of base 15, within the bulb 24, the portions of the leading-in wires within the bulb, indicated at 29, are of nickel or other stiff strong wire. This construction gave rise to 80 certain difficulties which have been solved in the following manner: In the device as constructed, I use No. 22 platinum wire and nickel wire of the same gage. There is no difficulty in securing these wires together by 85 methods which are well known. In order, however, to have the copper wire of the same carrying capacity electrically as the platinum and nickel sections, I have found it necessary or at least advisable to use a 90 No. 18 copper wire. In attempting to join the copper to the platinum the wires were attached to a source of supply of electric current, the other ends brought together and then drawn apart so as to cause arcing. This fused the platinum wire but not the copper. So far, of course, the method employed is old. In order to fuse the copper I placed the end of the copper wire in a gas flame drawn to a fine point by an air blast 95 and heated the copper to redness or somewhat hotter, then brought the platinum wire into contact with the heated copper wire, both wires being connected to the source of current supply, then drew the ends of the 100 wires slightly apart, and an arcing resulted which fused both wires. While this method of producing a greater amount of heat in one of two elements by supplementing the action of the flame with that of an electric current is especially adapted for and desirable in the step in the manufacture of my lightning arrester, as described, it is obvious 105 that this method might be employed in other situations.

In Figs. 7, 8 and 9 I have illustrated a preferred form of mounting for the lightning arrester of my invention, the device being obviously suitable for use with other apparatus of a similar character. 30 represents a porcelain block which may be permanently secured to a switchboard or other supporting means by any suitable means (not shown). This block has the binding posts 31 for the leading-in wires 25 from the line wire B (see Fig. 5) and the binding post 32 for the ground wire 26, the latter securing to the block 30 a coupling plate 33. 34 is a porcelain block on which is mounted 110 the lightning arrester or other similar piece 115 120 125 130

of apparatus. This block has secured there-to the coupling plate 35 which may be at-tached to the coupling plate 33 by the screw 36; and the coupling plates 37, 37 which 5 may be secured to the block 30 by the screws 38. The end 26^a of the ground wire 26 con-nects the plate 35 with the electrode 17. Sections of wire 25^a, 25^a connect the elec-trodes 16 with the plates 37 and sections of 10 wire 25^b, 25^b connect the binding posts 31 with the corresponding screws 38. The block 34 is slotted as indicated at 39. By this arrangement, when it is necessary to 15 remove the lightning arrester for repair, or 20 in order to replace it with a new one, by re-moving screw 34^a and screws 38, block 34 may be detached from block 30 without dis-turbing the connections of the ground and line wires.

20 The device, as above described, will oper-ate as follows: If a static discharge of short duration, even though it be of very high po-tential, gets on the line B, it will arc across the gap between the electrode 16 connected 25 with the part of the line wire in question to the electrode 17 and thence to the ground. A discharge of this sort will be so distributed over the electrodes and will be of such 30 relatively short duration that, if the device is properly designed, the electrodes will not be overheated, nor will enough current be 35 concentrated in and around the bodies of solder 22 to melt them. It will be under-stood that the device is designed, having ref-erence to the size of the gap and the inten-sity of the vacuum to give a resistance high 40 enough to prevent the normal current on the line from grounding. Now if the line should by chance be crossed with a high potential 45 line for example, say a line carrying 500 volts or more, the continuous current which would go over the gap between the elec-trodes, supposing them not to be provided with the balls, as above described, would in time result in heating the device to a point where it would be destroyed or made useless. This is what sometimes occurs with light-ing arresters constructed on this general principle. If, however, the electrodes 16 are 50 provided with the balls 23 the high continu-ous potential current will concentrate on the ball in question and will melt the solder which holds it in its cup, causing the ball to fall out of the socket against the grounded 55 electrode 17. As the ball is too large to es-cape from the space between the electrodes it closes the gap between them for the current and thereupon the heating of the electrodes ceases. With the device in this condition the 60 line B is, of course, grounded and out of service. When the cross has been discovered and repaired the lightning arrester may be re-moved in the manner above described, and the proper wires connected in a battery cir-cuit which will result in the melting of the

solder sufficiently to allow the displaced ball to be put back into its cup. When the solder has cooled the lightning arrester is again ready for service.

The electrodes are preferably mounted 70 upon the base 18 in order that their relative positions may be accurately fixed and main-tained. If each electrode is supported on its leading-in wire, the heating of the wires or other disturbances may cause a displacement 75 of one electrode with respect to the other, which interferes with the proper operation of the device.

In Fig. 6 I have illustrated diagram-matically an arrangement of a lightning ar-80 rester, constructed on the above principles for use in connection with a grounded cir-cuit, there being in this case only two elec-trodes. A' represents the instrument to be protected, B' the line wire which is grounded 85 as shown, 16^a an electrode connected with the line wire by the wire b and 17^a an electrode connected with the line wire on the other side of instrument A' by the wire b'.

As modifications in form, construction, 90 arrangement and proportion of parts will readily suggest themselves to those skilled in this art, I do not limit myself to these par-ticulars except so far as certain of the same may be made specific limitations on certain 95 of the claims herein.

Certain features of my invention, such, for example, as the use of the solder sup-ported iron balls are adaptable for use in air gap arresters as well as in vacuum arresters. 100

I claim:

1. A lightning arrester comprising a pair of electrodes spaced so as to form a gap and a contact element secured to and in electrical contact with one of said electrodes and out 105 of contact with the other which is moved into contact with the other of said electrodes by the heat generated at the gap due to an abnormal discharge across said gap.

2. A lightning arrester comprising a pair 110 of electrodes arranged so that an open space inter-venes between the same which can be traversed by a discharge without injury to said electrodes, a contact element and a fus-ible material which is melted by a continued 115 discharge of abnormal voltage and by re-leasing said contact element allows the same to close the space between said electrodes.

3. A lightning arrester comprising a pair 120 of electrodes spaced so as to form a gap, a contact element, and a fusible material which secures the contact element to and in elec-trical contact with one of said electrodes and out of contact with the other, said contact element when released adapted to come into contact with said other electrode and close 125 said gap.

4. A lightning arrester comprising a pair 130 of carbon plates spaced apart, a metal ball, and a fusible material which secures said ball

to and in electrical contact with one of said carbon plates and out of contact with the other; said ball being adapted when released by the melting of the fusible material to come into contact with said other plate and close the gap between said plates.

5. A lightning arrester comprising a pair of carbon plates, a cup secured to one of said plates, a body of solder in said cup, and 10 a ball secured to said cup by said solder; said ball being adapted when released by the melting of the solder to close the gap between said plates.

6. A lightning arrester comprising in combination a vacuum chamber, a pair of electrodes arranged in said chamber so that an open space intervenes between them, a contact element, and a fusible element which normally holds said contact element out of 15 electrical contact with one of said electrodes and which is adapted to be melted by a continued discharge of abnormal voltage so as to release said contact element and allow the same to close the space between said electrodes.

7. A lightning arrester comprising a pair of carbon plates, a cup secured to one of said plates, a body of solder in said cup, a ball secured to said cup by said solder; said ball 20 being adapted when released by the melting of the solder to close the gap between said plates, and inclosing means for said plates and ball from which the air has been partially exhausted.

8. In a lightning arrester, the combination with a base of non-conducting material, of a plurality of electrodes spaced apart and rigidly fixed to said base, and wires which support the base, the ends of which are bent 25 over and bound against the under surface of the base, and means extending through said base for maintaining said wires in electrical connection with said electrodes.

9. In a lightning arrester, the combination with a glass bulb having a stem, of a base of non-conducting material within said bulb, a plurality of electrodes spaced apart and rigidly fixed to said base, wires sealed through the neck of the bulb and bent over 30 and bound against the under surface of said base, and means extending through the base for maintaining said wires in electrical connection with said electrodes.

10. In a lightning arrester, the combination with a glass bulb having a neck, of a porcelain base in said bulb, a plurality of carbon plates spaced apart, a body of asbestos cement securing said carbon plates to the base, leading in wires sealed through the 35 neck of said bulb and bent over and bound to the under side of said base, and means extending through the base for maintaining said wires in electrical connection with said electrodes.

11. A lightning arrester comprising in

combination a vacuum chamber, a pair of electrodes arranged in said chamber so that an open space intervenes between them, a contact element, and a fusible material which secures said element to and in electrical contact with one of the electrodes; said fusible material adapted to be melted by a continued discharge of abnormal voltage so as to release the contact element and allow it to bridge the space between said electrodes.

12. A lightning arrester comprising the combination with an exhausted container, of a base of non-conducting material mounted within said container, a plurality of electrodes spaced apart and mounted upon said base, and wires sealed through the container and connecting with the electrodes.

13. In a lightning arrester, the combination with an exhausted glass container, of leading-in wires sealed through the wall of said container, a base of refractory, non-conducting material within said container and spaced away from the seals of the leading-in wires, a plurality of electrodes mounted on the opposite side of said base from the leading-in wires, and means electrically connecting the leading-in wires with said electrodes.

14. In a lightning arrester, the combination with a glass bulb having a stem, of a base of non-conducting material within said bulb, a plurality of electrodes spaced apart and mounted upon said base, wires sealed through the neck of the bulb, and means extending through the base for maintaining said wires in electrical connection with said electrodes.

15. In a lightning arrester, the combination with a glass bulb, of a base of non-conducting material within said bulb, a plurality of electrodes spaced apart and mounted upon said base, wires sealed through said bulb and in electrical connection with said electrodes respectively, said wires being arranged to support said base out of contact with the wall of said bulb.

16. In a vacuum lightning arrester, the combination with an evacuated glass container, of a leading-in wire sealed through the glass wall of the same, a base member of non-conducting refractory material supported on said leading-in wire and spaced away from the seal thereof, and an electrode supported on the opposite side of said base member from the seal of the leading-in wire and electrically connected through the base with said wire, said base being arranged transversely with respect to the leading-in wire so that it provides a shield intervening between the said electrode and the seal of said leading-in wire.

17. In a vacuum lightning arrester, the combination with an evacuated container, of a plurality of substantially parallel leading-

in wires sealed through the wall of said container, a base supported on said wires and spaced away from the seals of the same, a plurality of electrodes supported on the opposite side of the base from said seals and electrically connected through the base with said leading-in wires respectively, said base member being arranged transversely with

respect to the leading-in wires so that it provides a shield between the electrodes and the 10 seals of said leading-in wires.
